Patented Oct. 27, 1914.

UNITED STATES PATENT OFFICE.

WALTER E. NUTTER AND GEORGE P. ZELLER, OF ST. LOUIS, MISSOURI; SAID NUTTER
ASSIGNOR TO SAID ZELLER.

ICE-CAN FILLER.

1,114,797.

Specification of Letters Patent. Patented Oct. 27, 1914.

Application filed January 17, 1914. Serial No. 812,799.

To all whom it may concern:

Be it known that we, WALTER E. NUTTER and GEORGE P. ZELLER, citizens of the United States, residing at St. Louis, State of Missouri, have invented certain new and useful Improvements in Ice-Can Fillers, of which the following is a full, clear, and exact description, reference being had to the accompanying drawings, forming a part hereof.

Our invention has relation to improvements in ice-can fillers; and it consists in the novel details of construction more fully set forth in the specification and pointed out in the claims.

In the drawings, Figure 1 is an elevation looking at the narrow side of an ice-can, with parts broken away, showing our invention applied thereto, and set to filling position; Fig. 2 is a horizontal cross-section on the line 2—2 of Fig. 1, with can in top plan and turned ninety degrees from the position shown in Fig. 1; Fig. 3 is a top plan of the hollow staff or water delivery pipe and operating devices mounted thereon; Fig. 4 is a vertical longitudinal section on the line 4—4 of Fig. 3, parts being left in elevation; Fig. 5 is an elevational view looking to the left of Fig. 3; Fig. 6 is a vertical sectional detail through the middle of the valve-casing; and Fig. 7 is a cross-section on the line 7—7 of Fig. 6.

The object of our invention is to construct an ice-can filler which will automatically cut off the supply of water to the can when the proper level of the liquid in the can has been reached; one in which an air-tight joint is maintained about the valve-stem in the stuffing-box traversed by said stem; one in which the height of the water in the can may be regulated; one preventing the influx of atmospheric air into the water delivered to the can, thus avoiding the formation of white ice, or one in which air bubbles are confined; one which is simple in construction, reliable and uniform in operation; and one possessing further and other advantages better apparent from a detailed description of the invention, which is as follows:

Referring to the drawings, C represents a conventional ice-can to which the water to be frozen is delivered, said can being open at the top. Through the open end of the can is inserted the filler, the same comprising

ing a hollow tubular staff 1 to the bottom of which is screwed a valve-casing 2, to which in turn is secured and shouldered a bottom ring 3 provided with feet or projections 4 resting on the can bottom, the spaces *h* between the said feet forming passages for the discharge of the water into the can. The ring 3 forms a seat for the valve V to which seat the valve is normally forced and held by a compression spring 5 encircling the valve-stem 6 traversing the staff 1, and bearing with its opposite ends respectively against the valve and the guide-rib or spider *w* of the casing, the valve-stem 6 operating freely through said spider.

Disposed at convenient points along the staff 1 and spaced apart are collars or fittings 7 provided with radial bosses 8 to which are secured the ends of the members 9, 9, constituting the guide-frame, and of the members 10, 10, which constitute the guard-frame respectively, the guard-frame being intended in the main to protect the float F sliding freely along the staff 1, a spring 11 resting on the bottom collar 7 serving as a buffer for the float when the latter drops to its lowest position. The frame 9, 9, is provided with diagonal corner portions 9', 9', by which the device is better guided into the can, while being inserted thereinto, it being understood that the frame 9, 9, is of sufficient dimension to engage the diagonal corners of the can (Fig. 2), whereby the filler is held against any possible displacement when once inserted into the can and during the filling operation.

The upper end of the valve-stem 6 traverses a stuffing-box 12 at the upper end of the hollow-staff or pipe 1, said stuffing-box being positioned at the outer bend between the staff 1 proper and the horizontal intake extension or goose-neck 1' to which the water-supply hose H is directly secured or coupled.

To the upper free end of the valve-stem 6 is screwed (or otherwise secured) a cross-bar or cross-head 13 from the opposite ends of which depend pivotally the parallel links 14, 14, the links extending a suitable distance below the upper end of the stuffing-box 12. The lower ends of the links are pivotally secured to the fork arms 15, 15, of the valve-lever 15' which is pivotally secured at the base of the arms 15, 15, to an ear or lug

16 formed along the upper edge of a rib 17 preferably cast integral with the members 1, 1', and with the outer section of the stuffing-box 12 (though the rib might be otherwise secured to the pipe 1').

Surrounding the stuffing-box 12, and free to oscillate in a vertical plane about a pin α disposed transversely of the rib 17, and spanning said rib, is a ring or yoke 18, the same being provided with a post or latch 19 leading upwardly from a point adjacent the axis of oscillation of the ring, and disposed substantially at right angles to the plane of the ring. The upper free end of the post is provided with a shoulder m and an offset or ledge n at the base of the shoulder, for the support of the central nose 20 formed on the cross-bar 13, the post having a concaved formation or depression d on its inner face directly beneath the ledge n . The outer end of the ring or yoke 18 has formed thereon, or otherwise secured thereto an arm or lug 21 through which is inserted the upper screw-threaded end of the depending tripping rod or lever 22, the same being held in any vertically adjusted position in said lug 21 by means of jam-nuts t , t , as well understood in the art. The lower end of the rod 22 curves outward to as to ride freely over the spherical surface of the float F, when the latter engages the same in its upward movement with the rise of the water in the ice-can C.

The fork-arms 15, 15, may be regarded as jointly forming the short lever-arm of the lever 15', the plane of disposition of said arms being inclined to that of the long arm or lever 15' proper, and dipping downward therefrom (see Figs. 1, 4), whereby a maximum length may be imparted to the links 14, 14, a feature of some importance in preventing lateral binding on the valve-stem. The proximity of the post or latch 19 to the valve-stem also contributes toward maintaining the upper projecting end of the stem in true alinement with the portion confined in the staff 1. The stem then works true in its stuffing-box maintaining a tight joint therein, and there is no possible chance of outside air leaking, or being drawn through, the stuffing-box around the stem into the staff 1 to mingle with the inflowing water. The result is that when the charge of water is frozen, no air is confined in the ice mass and the latter is perfectly transparent and compact.

The operation of the filler may be described as follows:—The yoke 18 with the arm 21 and the post or latch 19 operate, and in fact constitute a bell-crank, the arm 18, 21, thereof being weighted and normally tending to drop to horizontal position, the rod 22 depending therefrom contributing largely to the weight of said arm. By tripping the rod 22 outwardly, the latch 19 be-

comes disengaged from the nose 20 of the cross-head 13 of the valve-stem 6 leaving the valve V of the stem thus disengaged, to be seated against the ring 3 and cutting off the water discharge, the stem 6, being pulled down with the seating of the valve, and the lever 15' being tilted upwardly, the links 14, 14, pushing down on the fork arms 15, 15 (see dotted position Fig. 4, and seated position of the valve in Fig. 6). With the valve thus seated, the filler is inserted into a can as shown in Figs. 1 and 2, and the valve-lever 15' is depressed (Figs. 1, 4), a depression of the lever causing the forks 15, 15, to push up on the links 14, 14, the latter raising the cross-head 13 attached to the valve-stem 6, whereby the valve V is opened or unseated allowing the water to discharge from the staff 1 into the tank C. With the raising of the valve V to open position, the latch 19 (previously tilted out of engagement with the nose 20) will, under the weight of the members 18, 21, 22, automatically reengage itself with the nose 20, the ledge n being brought under the nose, and the shoulder m arresting the latch by striking the edge of the nose (Figs. 1, 4). At the same time the lever 22 will oscillate toward the staff 1. When sufficient water accumulates in the tank C, it will pick up the float F and carry it upward until the float engages the lower curved end of the tripping lever 22. As the float continues to rise it trips said lever outwardly, thus causing the bell-crank 18, 21, 19, to be tilted to the dotted position shown in Fig. 4 (the same position resorted to when the device is first set for operation) disengaging the latch 19 from the nose 20, and allowing the spring 5 to automatically close the valve and cut off the water, the depression d on the latch 19 preventing any binding of the parts. The apparatus with its valve closed, is then removed from the filled can and deposited into another empty can, the lever 15' is depressed (toward the intake extension 1') whereupon the valve V is picked up or unseated, the latch 19 again automatically reengaging the nose 20, the parts being thus restored for delivering a charge of water into the next can C (Fig. 1). This operation is repeated, depending on the number of cans to be filled.

Obviously, the filler is not restricted to ice-cans, but may be employed for partially or wholly filling any liquid container.

It will be noticed that by the dipping of the fork members 15, 15, downward from the lever 15' proper, a maximum length may be given the links 14, 14, their lower ends extending below the top of the stuffing-box 12. In this way the arcs described by the sweep of the links are generated by radii of maximum length, which give the arcs a gradual curvature, resulting in practically no binding (lateral) on the valve-stem. The stem

thus works true in its stuffing-box and the danger of air leaking into the staff 1 does not arise. The closeness of the latch 19 to the valve-stem likewise contributes to the permanent trueness of reciprocation of the stem in its stuffing-box.

To protect the tripping lever 22 against lateral displacement out of a vertical plane passing through the axis of the staff 1, the latter is provided with a slotted guide bracket 50 clamped to the staff at a proper height to clear the float F when said float is in its highest position. A screw 51 secures the bracket in its vertically adjusted position, though any equivalent means may be resorted to.

Having described our invention, what we claim is:

1. A filler for liquid containers comprising a hollow staff having intake and discharge means for the liquid, a bottom discharge-control valve in the staff, a casing for the valve, a spring in the casing actuating the valve in one direction, a valve-stem leading from the valve through and beyond the staff, a stuffing-box for the upper end of the stem, a cross-head terminating the upper end of the valve-stem beyond the stuffing-box, a valve-lever pivoted adjacent the intake and provided with downwardly inclined fork members, parallel links depending from the cross-head and coupling to the fork-members at a point below the upper end of the stuffing-box, an oscillating latch coöperating with the cross-head, a float riding on the hollow-staff and responding to the buoyant action of the liquid, and intermediate connections between the float and latch for disengaging

the latter with a predetermined discharge of liquid.

2. A filler for liquid containers comprising a hollow staff having intake and discharge means for the liquid, a bottom discharge-control valve in the staff, a valve-stem leading from the valve centrally through and beyond the staff, a stuffing-box for the upper portion of the stem, a cross-head at the free upper end of the stem, a laterally projecting nose on the cross-head, a forked bent valve-lever pivoted adjacent the intake, links depending in vertical planes from the cross-head and coupling to the fork members of the lever, a bell-crank oscillating in a vertical plane pivoted at a point between the stuffing-box and the axis of oscillation of the valve-lever, said bell-crank comprising a weighted horizontal yoke-arm or ring enveloping the stuffing box and a vertical post or latch terminating in a supporting ledge adapted to shoulder against the nose of the cross-head, an adjustable tripping arm or lever mounted on the weighted arm of the bell-crank, and extending downward, a float riding along the staff for engaging and tripping said arm, and a spring in the staff for seating the discharge-control valve with a release of the post from the nose of the cross-head.

In testimony whereof we affix our signatures, in presence of two witnesses.
